UNITED STATES PATENT OFFICE.

ANTOINE LACROIX, JR., OF BROOKLYN, ASSIGNOR TO THE CO-OPERATIVE
BUILDING PLAN ASSOCIATION, OF NEW YORK, N. Y.

DESIGN FOR THE EXTERIOR OF A HOUSE.

SPECIFICATION forming part of Design No. 20,087, dated August 12, 1890.

Application filed July 15, 1890. Serial No. 358,850. Term of patent 7 years.

To all whom it may concern:

Be it known that I, ANTOINE LACROIX, Jr., of the city of Brooklyn, in the county of Kings and State of New York, have invented and 5 produced a new and original Design for the Exterior of a House, of which the following is a specification, reference being had to the accompanying drawings, forming a part thereof.

Figure 1 represents a perspective view of a 10 house showing my design. Fig. 2 represents a horizontal section or plan of the first story. Fig. 3 represents a horizontal section or plan of the second story.

Similar letters of reference designate corresponding parts in all the figures.

A house of this design consists of two stories and an attic third story within a gable roof, and has an L-shaped extension projecting rearwardly, a portion of which at the first 20 story being wider than that at the second story, such portion being covered by a sloping roof, an octagonal bay in the front thereof, the roof of which at the second story forms the floor of a balcony at the third story, and 25 a peaked roof surmounting the whole, a veranda extending along a portion of one side of the house, round the front thereof, and terminating on the opposite side at the point where the extension joins the main portion of 30 the house, said veranda being covered by a sloping roof, all as hereinafter to be more particularly described with reference to the drawings.

A B C designate the exterior of the first 35 and second stories and attic, the said attic be-

ing contained in a gable roof D, from which dormer-windows d, having peaked roof e, project. The front of the house has an octagonal bay a at the first and second stories, the roof of which above the second story forms 40 the floor of the balcony b at the third story, the whole being surmounted by a peaked roof c, branching from the gable roof D.

At the rear of the house is an L-shaped extension E F, the portion E having a bay G at 45 the first story, a flat-faced portion G' at the second story, and a third or attic story contained in the gable roof g. The other portion F of the extension is wider at the first story than at the second, the said wider portion being 50 covered by a sloping roof f. An additional portion H also projects from the rear at the first story.

A veranda I extends from about the middle of one side of the main portion of the house 55 along the front thereof and terminates on the opposite side at the angle formed by the junction of the portion E of the extension. The portion I of the veranda is covered by a sloping roof i, and is finished on the front by a 60 gable k, surmounting an entrance-porch K. The portion J is surmounted by a sloping roof j.

What I claim as my design is—

The design for the exterior of a house, substantially as herein shown and described.

ANTOINE LACROIX, JR.
